UNITED STATES PATENT OFFICE

FRANK O'NEILL, JR., OF NEW YORK, N. Y., ASSIGNOR TO THE FARGO CORPORATION, OF BROOKLYN, NEW YORK, A CORPORATION OF NEW YORK

APPARATUS FOR THE MANUFACTURE OF WIRE PULL BOTTLE CAPS

Application filed April 16, 1932. Serial No. 605,597.

This invention relates to an apparatus for use in connection with the manufacture of paper-disk bottle caps of a kind intended for use in milk bottles and other like receptacles. The particular type of bottle cap manufactured by the use of the apparatus to which this invention relates, consists of a paper disk which fits snugly in the bottle neck and rests on a seat formed therein, and is provided with a wire handle or "pull" by which it may be manually withdrawn from its seat. The wire handle or "pull" consists of a single piece of wire bent to a substantially U-shape and formed with a pair of legs which extend downwardly through the cap to reach its under face where they are projected laterally and then curled upwardly to pass through the cap to its upper face where they are then curled downwardly. After a wire pull of this kind has been inserted in a sheet of paper from which the disk is subsequently stamped, the parts of the pull located both on the upper and under sides of the sheet are imbedded in the sheet. The finished disk ready for insertion in a bottle, has no parts of the wire pull protruding from either its under or upper faces, so that these disks may be employed in a capping machine with the facility of the usual disk in which a wire pull is not incorporated.

The apparatus to which this invention has reference is one which operates upon the continuous sheet or web of paper from which these disks are formed, to align or position the wire pulls previously inserted in the sheet and to embed the wire pulls in the sheet. It also operates to produce a depression in each cap in the sheet adjacent to the handle portion of each wire pull, to enable the wire pull to be easily engaged by the finger-nail and raised preparatory to removing the cap from its seat in the bottle neck.

The object of the invention is to provide an apparatus of the character described which will successfully and speedily operate upon the continuous sheet or web of paper from which the caps are subsequently stamped and in which the wire pulls have

been previously inserted. The improved apparatus serves to first align and position the inserted pulls relative to embedding dies, and then embed them in the opposite faces of the sheet, and simultaneously with the embedding operation, to provide a depression in the sheet adjacent each pull for the purpose of permitting an easy finger-engagement of the pull.

In the accompanying drawings Fig. 1 is a plan view, partly in section, of the improved aligning and embedding device, with a portion of the paper sheet in position to be operated on; Fig. 2 is a sectional view on the line 2-2 of Fig. 1, looking in the direction of the arrows; Fig. 3 is a plan view of a completed cap; Fig. 4 is a view of the under face of the cap, the under layer or lamina being omitted; Fig. 5 is a view of the aligning and embedding means, looking upward from beneath the same; Fig. 6 is a sectional view on the line 6-6 of Fig. 5, looking in the direction of the arrows; Fig. 7 is a sectional view on the line 7-7 of Fig. 5, looking in the direction of the arrows; Fig. 8 is a sectional view on the line 8-8 of Fig. 1, looking in the direction of the arrows; Fig. 9 is a sectional view on the line 9-9 of Fig. 5, looking in the direction of the arrows; Fig. 10 is a vertical sectional view through one of the aligning and embedding die members; Fig. 11 is a sectional view through the finished cap on the line 11-11 of Fig. 3, looking in the direction of the arrows; and Fig. 12 is a sectional view on the line 12-12 of Fig. 3, looking in the direction of the arrows.

In Figs. 3 and 4 of the drawings is shown one of the bottle caps. It is composed of cardboard and is stamped from a sheet or web 13 after the wire pull or handle 14 has been inserted and embedded in it. These wire handles or pulls are inserted in the sheet or web 13 in the staggered relationship shown in Fig. 1, each pull being properly located with respect to the disk or cap defined in the sheet and of which it forms a part. The mechanism for inserting the wire pulls in the sheet 13 forms no part of this invention and is therefore not described.

Each wire pull consists of a substantially U-shaped section of wire composed mainly of the two parallel leg portions 15 integrally connected by a cross member 16. The parts 5 15 and 16 comprise the handle portion of the pull and are located on the upper face of the disk 17. The legs 15 are projected through the disk to its under face where they extend laterally at 18 and are curled 10 upward to pass through the disk to reach the upper face thereof where they terminate in the curved end portions 19 which are located on top of the disk and spaced from the leg portions 15. Thus, parts 15, 16 and 19 are 15 located on the upper face of the disk while the parts 18 are on the under face. All of these parts of the pull are embedded or sunk in the opposite faces of the disk by the apparatus of this invention.

20 The web or sheet 13 containing the inserted wire pulls 14 is fed along on a table or base 20 in the direction of the arrow 21 (Figs. 1, 6, 8 and 9) by any suitable intermittent feed mechanism not shown. Operating above the sheet 13 during the pauses in its movement along the table 20, is a plunger 22 which carries the mechanism for aligning and positioning the wire pulls and embedding them in the sheet. The plunger 25 consists of a plate carried on the supporting rod 23 and vertically reciprocated on the guide rods 23a, shown in Fig. 1. An eccentric or other suitable mechanism is used for reciprocating the plunger. Secured to the plunger by means of an angle bracket 24 is a plate 25 which is provided near its opposite edges with a number of downwardly projecting pilot pins 26. These pins are 30 threaded into the plate 25, as shown at 27 in Fig. 2, and are adapted to pass through holes 28 provided along the longitudinal edges of the sheet 13 during pauses in the movement of the sheet beneath the plunger. The longitudinal edges of the supporting table 20 35 are formed with channels 29 and the edges of the sheet 13 are moved in these channels as clearly shown in Fig. 2. Recesses 30 are provided in the channelled parts of the table 20 in registration with the pilot pins 26 so that the plunger 22, upon descending, will cause the pins 26 to enter some of the holes 28 in the sheet and the recesses 30, the movement of the sheet 13 being coordinated with the movements of the plunger to enable the 40 pins to engage the holes in the sheet on each descent of the plunger. When the pins 26 enter the holes in the sheet, the sheet is properly registered and is held stationary while the operation of aligning the wire 45 pulls and embedding them in the sheet is performed by mechanism carried by the plunger.

46 Fixed to the under side of the plunger 22 by the screws 31 is a plate 32 which is 50 grooved at 33. Each of these grooves ac-

commades a disk-like die member 34. These die members 34 are slidingly mounted in the grooves and are adapted to be shifted therein to the left of Figs. 6, 8 and 9 against the pressure of the springs 35. 55 The walls of the grooves 33 are formed with inclined portions 36, these inclined portions co-operating with correspondingly formed grooves in the sides of the dies 34 to positively guide the dies in their sliding movement.

The die members 34 are moved on their support 32 by means of a three-sided frame and connected parts. The frame consists of a longitudinal bar 37 secured to end bars 38 60 and 39. The longitudinal bar 37 is connected to the plate 32 by screws 40 which are fixed in the plate 32 and extend through slots 41 in the bar whereby a movable or sliding connection is established between the 65 bar and the plate. Bolts 42 secure the bar 37 to the end bars 38 and 39 so that the three bars 37, 38 and 39 are shifted as a unit, the ends of the plate 32 being grooved at 43 to positively guide the bars 38 and 39 in their 70 sliding movement.

Threaded in the bar 37 is a plurality of rods 44, each of these rods being adapted to slidingly shift one of the dies 34. Each rod 44 is threaded at 45 in the bar 37 and is 75 thus adjustable therethrough. A shoulder 46 is formed on each rod and the shoulder bears against the end of a bushing 47, the opposite end of which is held against the face of a die member 34, as shown in Fig. 6. 80 The inner end of the rod 44 is accommodated in a recess 48 formed in the die member. Through the adjustable rods 44 and cooperating bushings 47 the position of each of the die members relative to the three-sided 85 frame which slides these members on their supporting plate 32, is regulated. The lock nut 49 on each rod 44 holds the rod in its proper position of adjustment once the 90 proper setting thereof has been secured.

The die-shifting frame composed of the connected bars 37, 38 and 39 is slidingly shifted by means of cam surfaces, several of which are shown at 50 on members 51 secured at the opposite sides of the support 20. 95 Cap screws 52 attach these cam members to the table 20 as clearly shown in Figs. 6 and 8. The fixed cam surfaces 50 cooperate with cam surfaces 53 formed on the end of the bars 38 and 39. When the plunger 22 descends, the cam surfaces 53 will be 100 brought into contact with the cam faces 50 on the fixed cam members 51 whereby the frame composed of the bars 37, 38 and 39 and associated parts, will be shifted in the 105 direction of the arrow 21, or in a direction at right angles to the movement of the plunger and parallel to the plane of the plunger. This sliding movement of the frame causes the die members 34 to be slid- 110

ingly shifted in their grooves 33 against the pressure of the springs 35 which surround rods 54 threaded into a bar 55 attached to the edge of the plate 22. One end of each 5 spring bears against a die member 34, the opposite end of the spring bearing against a washer 80 impinging against the shoulder 81 on the rod. The inner end of each of the rods 54 projects into a recess 56 formed 10 in the die 34, the opposite end of each rod being threaded through the bar 55 and capable of being fixed in any position of adjustment by means of the lock nut 57.

Each of the die members 34 is provided 15 with a recess 58 within which a plunger 59 is movable. At its lower end the plunger 59 is formed with a die portion 60 which performs the functions of aligning or positioning the wire pull on each cap in the sheet 13 and forming a depression 61 in the cap to enable the cross-bar 16 of the pull to be easily raised by the finger-nail when the cap is to be lifted from its seat in a bottle neck. The plunger 59 is spring-pressed by the coil- 25 spring 62 which rests in a pocket 75 provided in the upper end of the plunger. The normal or inoperative position of the plunger is shown in Fig. 6; its fully compressed position being shown in Fig. 10. At its upper end the plunger 59 is provided with a head 76 which, when the die member 34 has reached its completely descended position, abuts against the under face 76a of the plate 32 and holds the die portion 60 rigid relative 30 to the die 34 causing the end 73 of the die portion 60 to form the indentation 61 in sheet 13.

The bottom surface of each of the die members 34 is formed with raised die elements 71 and 72. These raised die elements are shaped to cover and embed the portions 40 15, 16 and 19 of the wire pull. That is to say, the die element 71 is substantially U-shaped and serves to embed the cross bar 16 and legs 15 in the top surface of the sheet 13. Similarly, the die elements 72 are of a shape to embed the ends 19 of the pull. The face of the die element 71 is slightly inclined so that the legs 15 are more deeply 45 embedded in the cap near the point where they pass through it, than at the cross bar. This will be apparent from Fig. 11 where the inclined position of the legs of the pull when embedded is clearly shown.

50 Briefly, the operation of the apparatus is as follows:—

The sheet 13 in which a large number of caps are defined, and in which the wire pulls 55 14 have been inserted as shown in Fig. 1, is fed along on the support 20 beneath the plunger 22 by any suitable intermittent feed mechanism. The wire pulls have their leg portions 15 and connecting cross-bar 16 extending upward at an angle from the face 60 of the sheet as shown in Figs. 8 and 9. Dur-

ing a pause in intermittent feed of the sheet 13, the plunger 22 descends and the pins 26 carried by the plunger enter into some of the holes 28 formed at the side edges of the sheet 13, thus holding the sheet against any shifting movement while the alignment and embedding of the wire pulls takes place. As the plunger 22 descends, the cam surfaces 53 are brought into contact with the surfaces 50 on the fixed cam members 51 70 whereby the frame carrying the rods 44 is slidingly shifted in the direction indicated by the arrow 21. At the beginning of this shifting movement the plunger has partly descended and the parts are substantially 80 in the position shown in Fig. 6. The rods 44 and bushings 47 slide all of the die members 34 to the left of Fig. 6, this action causing the face 70 on each of the die portions 60 to be brought into forcible contact with one of the cross bars 16 of a wire pull whereby the wire pull is aligned or straightened preparatory to being embedded in the sheet 13. This action of the die portion 60 will 85 be more readily understood by reference to Fig. 6 where the face 70 on the die portion 60 is about to be brought into contact with the cross bar 16 of the wire pull indicated at 14a, to properly align and position this wire pull with respect to the embedding die portions 71 and 72.

This aligning and positioning action is necessary due to the fact that the movement of the sheet 13 along on its support 20 prior to reaching a point beneath the plunger 22 often causes the wire pulls to be misaligned 100 or twisted relative to the sheet. In some cases the frictional contact of the parts 18 of the wire pulls with the face of the support 20 is sufficient to project the parts 15 105 and 16 out of the sheet to a greater extent than is necessary. The action of the face 70 in forcibly contacting with the cross bar 16 is such as to align and position the wire pull relative to the sheet to which it is attached so that uniformity and proper placement of the wire pull in each cap is assured.

110 After the face 70 of each die portion 60 has acted, by the sliding movement of the die members 34, to align and position the wire pulls in the sheet 13, and the descent of plunger 22 continues, the embedding of the parts of the wire pull occurs. This embedding operation is performed by the die elements 71 and 72 which embed the parts 115 15, 16 and 19 of the pulls in the upper face 120 of the sheet. While the parts 15, 16 and 19 of the pulls are being embedded by the pressure of the die portions 71 and 72, the depression 61 is being formed in the top face 125 of the cap by the action of the inclined lower end 73 of the die portion 60, as clearly shown in Fig. 10. The plunger 22 is then raised and the sheet 13 is moved to bring 130 the next group of caps in the sheet below the

plunger in readiness for its next descent. Since the under face of the sheet 13 is firmly pressed against the face of the table 20 by the pressure of the embedding dies, the 5 curved portions 18 of each wire pull, which are situated on the bottom of each cap, are embedded in the bottom face of the sheet. Consequently, when the sheet issues from the embedding mechanism all portions of the 10 wire pulls have been embedded, and the caps 17 when stamped from the sheet 13 have no projecting parts which might interfere with their use in a capping machine of the conventional type in use at the present time. If desired, a protective lamina or layer 90 may be secured by an adhesive to the under face of the cap to cover the parts 15 18 of the pulls and incidentally close the minute holes formed in the cap by the passage of parts of the pull through it. Such a layer 90 is preferably secured to the under face of the sheet before the caps are stamped from it.

What I claim is:—

25. 1. A device of the class described comprising a support on which a paper sheet containing a plurality of aligned inserted wire pulls is held, means for embedding portions of the wire pulls in the sheet, and means acting in advance of the embedding means for shifting the position of unaligned wire pulls to align them with the other wire pulls previous to their embedding in the sheet.
35. 2. A device of the class described comprising a support on which a paper sheet containing a plurality of aligned inserted wire pulls is held, means for embedding portions of the wire pull in the sheet, and means acting in advance of the embedding means for applying pressure on the inserted wire pulls lengthwise thereof to shift the position of unaligned pulls in the sheet prior to the action of the embedding means.
45. 3. In an apparatus for making paper-disk bottle caps, a support for holding a paper sheet in which wire pulls have been inserted, each of the inserted wire pulls lying at an inclined position relative to the sheet and having a pair of legs and a connecting cross-bar, means for applying pressure on the cross bars of the pulls to shift the pulls relative to the sheet and means for thereafter embedding the legs and cross-bars of the pulls in the sheet.
55. 4. In an apparatus for making paper-disk bottle caps, a support for holding a paper sheet in which wire pulls have been inserted, each of the pulls lying at an inclined position relative to the sheet and having a pair of legs and a connecting cross-bar at the top face of the sheet and curved portions at the under face of the sheet, means for striking against the cross-bars 60 of the pulls to longitudinally adjust the

70 pulls in the sheet, means for embedding the legs and cross-bars of the pulls in the upper face of the sheet and causing the curved portions of the pulls to be embedded in the under face of the sheet.

5. A device of the class described having a support for a paper sheet in which a plurality of wire pulls have been inserted, a reciprocating plunger carrying a die for contacting with and embedding parts of the wire pulls in the face of the sheet, and means movable at right angles to the movement of the plunger for contacting with parts of the wire pulls and positioning them with respect to the embedding means 75 just prior to the embedding operation.

6. An apparatus for making paper-disk bottle caps having a support for a paper sheet in which wire pulls have been inserted, a plunger carrying dies for embedding parts of the wire pulls in the sheet, movable die members for forming an indentation in the sheet adjacent to a cross member on each of the wire pulls, and means for imparting a horizontal sliding movement to said movable die members to cause the same to contact with and position the wire pulls in the sheet prior to the embedding and indentation-forming operation.

7. An apparatus for making paper-disk bottle caps having a support for a paper sheet in which wire pulls have been inserted, a reciprocating plunger, embedding dies carried on the under side of the plunger, a portion of each die being resiliently mounted, and means for imparting a horizontal sliding movement to each die to cause a part of the resiliently mounted portion to contact with and position the wire pulls in 105 the sheet and align the same with respect to the embedding dies.

8. An apparatus for making paper-disk bottle caps, having means for supporting a paper sheet in which wire pulls have been 110 inserted, a reciprocating plunger carrying dies, said dies having fixed portions for embedding parts of the wire pulls in the sheet, and having movable portions for forming indentations in the sheet adjacent to parts of the wire pulls, means for shifting the dies horizontally whereby the wire pulls are engaged by the movable portions of the dies and aligned and positioned in the sheet to receive the pressure of the fixed portions of the dies to embed the parts of the pulls in 115 the sheet.

9. An apparatus for making paper-disk bottle caps having means for supporting a paper sheet in which a plurality of wire pulls 125 have been inserted, a vertically reciprocating plunger carrying dies, means on the plunger for supporting the dies to permit of a horizontal sliding movement of the dies, the lower face of each of said dies being 130

formed with raised portions for embedding parts of the wire pulls in the sheet upon the lowering of the plunger, a vertically movable die portion resiliently mounted in each of the dies, and means for imparting a horizontal sliding movement to the dies upon the descent of the plunger to cause the wire pulls to be aligned in the sheet by operation of the resiliently mounted die portion against the pulls.

10. In an apparatus for making paper-disk bottle caps, means for supporting a paper sheet in which wire pulls have been inserted, a reciprocating plunger carrying a die, a slot in the plunger in which said die is slidably shifted in a direction transverse to the direction of movement of the plunger, raised surfaces on the under face of the die for embedding parts of a wire pull in the upper face of the paper sheet, a spring-pressed indentation-forming member mounted within the die and having a portion projecting below the under face of the die, and means for sliding the die to cause the indentation-forming member to strike a wire pull to align and position it in the sheet preparatory to having its parts embedded by the raised surfaces on the die.

11. In an apparatus for making paper-disk bottle caps, means for supporting a paper sheet in which wire pulls have been inserted, a reciprocating plunger carrying a die, a slot formed in the under face of the plunger in which the die is slidably mounted, raised surfaces formed on the under face of the die for embedding parts of a wire pull in the upper face of the paper sheet, a spring-pressed indentation-forming member mounted within the die and having its lower end projecting below the die, cam means for shifting the die relative to the plunger and at right angles to plunger movement, upon the descent of the plunger, to cause the indentation-forming member to strike a wire pull to align and position it in the paper sheet preparatory to having its parts embedded in the paper sheet by the raised surfaces on the die.

12. In an apparatus for making paper-disk bottle caps, a support for a paper sheet in which wire pulls have been inserted, a reciprocating plunger mounted to operate above the support, means carried by the plunger for holding the sheet stationary upon the descent of the plunger, a die slidably mounted on the under face of the plunger, cam means for shifting the die with a movement transverse to the direction of descending movement of the plunger, means on the die for contacting with and embedding parts of a wire pull in the upper face of the paper sheet, and a spring-pressed member carried by the die for striking a wire pull on the sliding movement of the die to position the pull relative to those parts on

the die which embed the parts of the wire pull.

13. In an apparatus for making paper-disk bottle caps, a support for a paper sheet in which a plurality of wire pulls have been inserted, a reciprocating plunger mounted to operate above the support, a plurality of dies slidably mounted on the under face of the plunger, embedding means on each die, a spring pressed indentation-forming member mounted in each die and having a portion extending below the die and normally projecting below the embedding means thereon, and cam means for simultaneously shifting the dies with a movement transverse to the direction of descending movement of the plunger to cause the indentation-forming members to contact with and align the wire pulls in the paper sheet before the pulls are reached by the embedding means.

14. In an apparatus for making paper-disk bottle caps, a support for a paper sheet in which a plurality of wire pulls have been inserted, the wire pulls having legs and a connecting cross-bar located above the sheet and inclined with respect to the same, a plunger mounted to reciprocate above the sheet, a die carried by the plunger, said die being formed with under parts for embedding the legs and cross bars of a wire pull in the top face of the sheet, and a member carried by the die for applying pressure lengthwise of the pull on the cross bar thereof to position the pull in the sheet before the embedding of the cross-bar and legs thereof occurs.

15. In an apparatus for making paper-disk bottle caps, a support for a paper sheet in which a plurality of wire pulls have been inserted, the wire pulls each having a pair of legs and a cross-bar located above the sheet and inclined with respect to the upper face of the same, a plunger mounted above the sheet for reciprocatory movement, a die carried by the under side of the plunger, said die having projecting under portions for embedding the legs and cross-bars of a wire pull in the top face of the sheet upon the descent of the plunger, a resiliently mounted member carried by the die for applying pressure on the cross-bar of a pull in the direction of the length of the pull to position the pull in the sheet before the embedding of the cross-bar and legs thereof occurs, and means on the resiliently mounted member for forming an indentation in the sheet adjacent to the embedded wire pull cross-bar.

16. In an apparatus for making paper-disk bottle caps, a support for a paper sheet in which a plurality of wire pulls have been inserted, a die member mounted to have a vertical and horizontal movement, embedding members on said die member and fixed relative thereto, an indentation-forming

member mounted for vertical movement in the die, means for resiliently projecting the lower end of said indentation-forming member out of the bottom of the die, and means for limiting the extent of retraction of the indentation-member within the die whereby a part of the indentation-forming member projects from the bottom of the die at the limit of movement of the die and forms an indentation in the sheet adjacent to a part of a wire pull that is embedded in the sheet.

17. In an apparatus for making paper-disk bottle caps, a support for a paper sheet in which a plurality of wire pulls have been inserted, a die for embedding a wire pull in the sheet, said die being mounted to have a vertical and horizontal movement, embedding members fixed on said die, an indentation-forming member mounted for vertical movement in the die, means for resiliently projecting the lower end of the indentation-forming member out of the bottom of the die, means for slidably moving the die in a substantially horizontal plane while the lower end of the indentation-forming member is projected out of the die to cause said member to contact with and align and position a wire pull in the sheet, and means for limiting the extent of retraction of the indentation-forming member within the die whereby a part of said member will project from the bottom of the die at the limit of its movement to form an indentation in the sheet adjacent to a part of a wire pull embedded in the sheet.

18. In an apparatus for making paper-

disk bottle caps, a support for a paper sheet in which a plurality of wire pulls have been inserted, each of the inserted wire pulls having legs and a connecting cross-bar, a plunger mounted above the sheet for reciprocatory movement, a plurality of slots in said plunger, a frame mounted on the plunger for limited sliding movement relative thereto, rods connected to the frame and movable therewith, dies mounted in the slots in the plunger and adapted to be shifted within said slots by the rods, springs for opposing the sliding movement of the dies, embedding means formed on the bottom of the dies, a spring-pressed indentation-forming member mounted in each die and means for limiting the upward movement of said indentation-forming member whereby a portion of the same is presented below the lower face of the die when said member reaches its limit of upward movement.

19. In an apparatus for making paper-disk bottle caps, a support for a paper sheet in which a plurality of wire pulls have been inserted, a vertically reciprocating plunger carrying dies, means on the plunger for supporting the dies to permit of a horizontal sliding movement of the dies, the lower face of each of the dies being formed with raised portions for embedding parts of the wire pulls in the sheet upon the lowering of the plunger, one of said raised portions having an inclined contacting face to angularly embed the portion of the pull with which it contacts.
